UNITED STATES PATENT OFFICE

2,671,159

TAPE DISPENSING MACHINE

Philip L. O'Donnell, Norwood, Ohio

Application July 2, 1952, Serial No. 296,855

5 Claims. (Cl. 219—19)

1

This invention relates to a machine for dispensing tape having a thermoplastic adhesive coating on one side or face. More particularly, the invention relates to a dispensing machine having a heater for heating such tape as it is dispensed from the machine for use.

An object of this invention is to provide a tape dispensing machine having a tape heater which heats tape as the tape is fed from a roll to the pressing foot of a tape applying machine.

Another object of this invention is to provide a tape heating element for heating the tape and a heat transfer unit or member for keeping the tape hot as the tape is fed from the heating element to the pressing foot.

A further object of this invention is to provide a heat conducting transfer member for a tape heating element which can be attached to one end of the heating element for guiding tape upwardly from the heating element to the pressing foot, which heat transfer member receives heat from the heating element by conduction.

The above and other objects and features of this invention will in part be apparent and will in part be obvious from the following detailed description, and the drawing in which:

Figure 1 is a plan view of a tape heating and dispensing machine constructed in accordance with an embodiment of this invention, the cover of the tape heater thereof being shown in raised position;

Fig. 2 is a view in section of the machine illustrated in Fig. 1, the section being taken along the heating element thereof;

Fig. 3 is a perspective view of a heat transfer member which forms a part of the machine;

Fig. 4 is a view in end elevation of the machine shown in Figs. 1 and 2; and

Fig. 5 is a view in section taken along a line V—V in Fig. 2 with the cover being shown closed.

In the following detailed description, and the drawing, like reference characters indicate like parts.

It is customary in the manufacture of women's shoe uppers to apply a French binding to the top edge and at the same time to apply a reinforcing tape to the opposite side of the upper.

The French binding is used to give a finished appearance to the shoes, whereas, the reinforcing tape is used to prevent stretching of the leather and to generally reinforce the edges of the thin materials used in women's shoes. A machine for applying French binding and reinforcing tape in a single operation is shown in my Patent No. 2,261,127.

2

As shown in Figs. 1 and 2 of the drawings, a machine 9 constructed in accordance with an embodiment of the present invention, guides reinforcing tape 12 from a spool 13. The tape 12 is provided with a coating on one face thereof of a thermoplastic adhesive which must be heated before the reinforcing tape is applied to a shoe. The adhesive may be of balata or the like which, when heated, will cause the tape to adhere to the leather of a shoe upper. The tape is heated by a heating element 14, which may be an electrical resistance heater having a suitable electrically insulating sheath or cover. The heater 14 is mounted on the top of a table 16, and the tape is guided above the heating unit 14 to be heated thereby, as indicated at 12a, and then is directed upwardly, as indicated at 12b, to the foot 17 of a machine for pressing the tape onto the edge of a shoe upper or the like. This machine may be of the type described in my Patent No. 2,261,127, and may be adapted to sew French binding on one side of an edge of a shoe upper while reinforcing tape is affixed to the other side.

The heating element 14 is mounted in a channel-shaped guideway 18 (Fig. 5), and the tape is guided above the heating element 14 so that the tape receives heat therefrom. The tape enters guideway 18 through an opening 18' in the bottom thereof and rides over an idle roll 18" with the coated side toward the roll. The tape then passes along the guideway to the right hand end thereof, as shown in Figs. 1 and 2. The right hand end of the heating unit carries a heat transfer member 19 through which the section of tape 12b extends upwardly. The heat transfer member 19 is formed of copper or other material of high heat conductivity so that the heat transfer member 19 receives heat from the heating element 14 and conducts the heat upwardly the length thereof. Member 19 is formed as shown in Fig. 3 to have an upper portion 21 of channel shape, a U-shaped bottom portion 22, and an intermediate or connecting portion 23. The U-shaped bottom portion 22 is adapted to slip over one end of the heating unit 14, as shown in Fig. 2, with the web of the upper portion extending upwardly thereabove. As shown in Fig. 2, the upper portion is spaced from the bottom portion so that the tape can pass between the upper and the bottom portions. The tape is guided by a roller 26. Roller 26 is mounted just below the lower end of the upper portion 21 so that the tape leaving the heating unit passes around roller 26 and upwardly between the flanges of the upper portion 21 of the heat transfer unit.

3

The heat transfer unit is surrounded by a tubular cover member 27. Member 27 is attached to the table 16 surrounding the heating member and spaced therefrom. The roller 26 is journaled in cover member 27. The cover member 27 is provided with a slot 28 in the side thereof opposite the open side of the channel-shaped upper portion 21 of the heat transfer member. The slot 28 is used for threading the tape through the heat transfer unit. A roller 29 is journaled in the upper end of tubular cover 27 to guide the tape as the tape leaves the top of the heat transfer member. As shown in Figs. 2 and 4, the tape makes a quarter turn inside the heat transfer member and leaves the heat transfer member and the tubular cover thereof closely spaced from presser foot 17 so that, once the tape is heated by passing above heating element 14, the tape is maintained hot by the heat transfer member and reaches presser foot 17 in heated condition.

As shown in Figs. 1 and 2, the machine is provided with a cover member 31 which is hinged to an auxiliary tape receptacle 32. The cover includes an inverted channel-shaped portion 33 which fits over the flanges of the tape guiding channel 18 as shown most clearly in Fig. 5. The flanges of cover portion 33 are spaced from the flanges of guide 18 to provide an insulating air space therebetween. In addition, an insulating pad 34 of asbestos or the like is attached to the web of cover 33 as shown in Fig. 5, to insulate the cover.

The auxiliary tape receptacle 32 may be used with other types of tape such as a tape having a pressure sensitive coating, and the operation of the auxiliary receptacle may be similar to the operation of the device shown and described in my Patent No. 2,261,127.

When auxiliary tape receptacle 32 is in use, an idle roll 34' may be attached to cover 31 for guiding tape from the auxiliary roll into the space above heating element 14. The roll 34' may be removed when tape is fed from below the table 16 from the roll 13.

The heating element 14 may be provided with a rheostat 36 as indicated in Fig. 1, by means of which the heating element may be adjusted. In addition, appropriate thermostatic controls, not shown, may be incorporated in the heating element for controlling the heat thereof.

The tape heater, described above and illustrated in the drawing, is subject to structural modification without departing from the spirit and scope of the appended claims.

Having described my invention, what I claim as new and desire to secure by Letters Patent is:

1. A tape heater for a machine for dispensing thermally responsive tape of the thermoplastic and pressure sensitive type, which comprises an elongated hollow, substantially horizontal tape guide, a flat elongated heating element in the lower portion of the tape guide, a heat transfer member of heat conductive material attached to the heating element at one end of the guide and extending upwardly therefrom to the foot of a tape applying machine, said heat transfer member comprising a substantially horizontal bottom portion of U-shape in section embracing the heating element to be heated by the same, an upper portion of upright channel shape spaced above the bottom portion and facing away from the tape guide and an intermediate plate portion connecting the bottom and upper portions

4

at one side of the tape guide, and means for guiding the tape through the tape guide and up between the flanges of the channel of the heat transfer member and spaced from the web and flanges thereof for heating the tape as the tape is delivered to the tape applying machine.

2. A tape heater for a machine for dispensing thermally responsive tape of the thermoplastic and pressure sensitive type which comprises an elongated hollow, substantially horizontal tape guide, a flat elongated heating element in the lower portion of the tape guide, a heat transfer member of heat conductive material attached to the heating element at said end of the guide and extending upwardly therefrom to the foot of a tape applying machine, said heat transfer member comprising a bottom portion embracing the heating element, an upper portion of upright channel shape spaced above the bottom portion and facing away from the tape guide, and an intermediate portion connecting the bottom and the upper portions at one side of the tape guide, and means for guiding the tape through the tape guide and up through the channel of the heat transfer member for heating the tape as the tape is delivered to the tape applying machine, said guiding means comprising a roller journaled adjacent the lower end of the upper portion of the heat transfer member.

3. A tape heater for a machine for dispensing thermally responsive tape of the thermoplastic and pressure sensitive type which comprises an elongated hollow, substantially horizontal tape guide, a flat elongated heating element in the lower portion of the tape guide, a heat transfer member of heat conductive material attached to the heating element at said end of the guide and extending upwardly therefrom to the foot of a tape applying machine, said heat transfer member comprising a bottom portion embracing the heating element, an upper portion of upright channel shape spaced above the bottom portion and an intermediate portion connecting the bottom and upper portions at one side of the tape guide, means for guiding the tape through the tape guide and up through the channel of the heat transfer member for heating the tape as the tape is delivered to the tape applying machine, and a hollow, protective cover surrounding the heat transfer member, said cover being provided with a slot extending the length thereof opposite the open side of the channel for threading the upper portion of the heat transfer member.

5. For use with a stitching machine a tape magazine and guide comprising means for holding a spool of tape, said tape having one of its faces coated with a thermoplastic adhesive, an elongated tape heating tunnel oven, a chimney extending upward from one end thereof, an aperture in the floor of said oven adjacent the end thereof spaced from said chimney, heat producing means disposed on and substantially covering the floor of said tunnel oven, said heat producing means being spaced below and extending across the mouth of said chimney to a point adjacent said aperture in the oven floor, a tape supporting guide roll adjacent said aperture, a tape hold-down guide roll adjacent the base of said chimney and spaced above said heat producing means, a tape supporting guide roll adjacent the top of said chimney, said aperture and guide rolls being adapted to co-operate with a tape as described to substantially limit such a tape to a predetermined path through said oven and chimney.

ney, a heat conducting member provided with a substantially tubular portion adapted to receive and engage the portion of said heat producing means disposed adjacent the chimney end of said oven, said member extending into said chimney and having a channel-shaped portion thereof disposed about the predetermined path of tape advance between the hold-down guide roll and the guide roll adjacent the top of said chimney whereby the adhesive on one face of said tape may be rendered sticky by heating said tape and may be delivered hot from the chimney mouth without said sticky face contacting any other surface while sticky.

5. A device according to claim 4 characterized by the fact that said tunnel oven is provided with a hinged lid, that the chimney end of said oven is open, that the top of said chimney is closed by a cover member, that in said cover member a slot is provided through which said

10

15

20

tape passes and that in said chimney a second slot is provided joining said first slot and said open tunnel oven end and in registry with the channel in said heat conducting member whereby threading of tape through said guide and heating means is facilitated.
